CLAIM

The ornamental design for a storage hanger, as shown and described.

DESCRIPTION

FIG. 1 is a top, front, left perspective view of a storage hanger showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, left perspective view showing my new design in an exemplary environment of a storage rack; and, FIG. 9 is a top, front, left perspective view showing my new design in an exemplary environment of a storage rack.

The broken lines immediately adjacent to the shaded area define the bounds of the claimed design and form no part thereof. The broken lines depicting the remainder of the storage hanger and the exemplary environment show features that form no part of the claimed design.
